[57] CLAIM

The ornamental design for a clock hand, as shown and described.

DESCRIPTION

FIG. 1 is a perspective view of a clock hand;
FIG. 2 is a front elevation view of a clock hand;
FIG. 3 is a side elevation view of the clock hand of
FIG. 2;

FIG. 4 is a top plan view of the clock hand of FIG. 2;
FIG. 5 is a perspective view of a collapsed form of a
clock hand; and,

FIG. 6 is a bottom plan view of the clock hand of FIG.
2.

The broken-line showings of FIGS. 1 and 5 are for
illustrative purposes only and form no part of the
claimed design.

FIG. 1

FIG. 4

FIG. 2

FIG. 3

FIG. 5

FIG. 6
